W. W. BROWN.

COMBINED COLLAR BUTTON AND TIE SLIDE,
APPLICATION FILED APR. 21, 1914.

1,146,688.

Patented July 13, 1915.

UNITED STATES PATENT OFFICE.

WILLIAM W. BROWN, OF SWANSON, SASKATCHEWAN, CANADA.

COMBINED COLLAR-BUTTON AND TIE-SLIDE.

1,146,688.

Specification of Letters Patent. Patented July 13, 1915.

Application filed April 21, 1914. Serial No. 833,561.

To all whom it may concern:

Be it known that I, WILLIAM W. BROWN, a subject of the King of Great Britain, residing at Swanson, in the Province of Saskatchewan and Dominion of Canada, have invented certain new and useful Improvements in Combined Collar-Buttons and Tie-Slides; and I do hereby declare the following to be a full, clear, and exact description of the invention, such as will enable others skilled in the art to which it appertains to make and use the same.

My invention relates to new and useful improvements in devices for securing collars to the neck band and slidably holding neck ties within collars and has for its principal object to provide a combined collar button and tie slide that will effectively hold neck ties in such a way that they may easily slide and not work up or down relative to the collar in sliding and also provide for an easy and expeditious securing of the collar to neck bands.

Another important object of my invention is to provide a simple and inexpensive device of the character described that is formed of a single piece of metal which is bent and twisted in a novel manner to provide a tie slide in combination with a spring button to facilitate securing of the collar.

Another important object of my invention is to provide a device of the character described that will automatically lock with relation to the neck band and also prevent pinching of the neck tie to enable easy sliding of the tie and prevents undue wear thereof.

The above and additional objects are accomplished by such means as are illustrated in the accompanying drawings, described in the following specification and then more particularly pointed out as claimed.

With reference to the drawings, wherein I have illustrated the preferred embodiment of my invention as it is reduced to practice, and throughout the several views of which similar reference numerals designate corresponding parts, Figure 1 is a vertical sectional view taken through a collar and neck band showing my improved device in operative position and in side elevation, Fig. 2 is a front elevation showing my improved device in operative position with a portion of the collar broken away, and Fig. 3 is a detail perspective view of my improved device.

With reference to the drawings it will be

noted that my improved device is formed of a single piece of preferably spring wire that is bent intermediate its ends to provide an elongated U-shaped loop 1 and bent back 60 from the open end of the loop on each side thereof to provide upwardly diverging arms 2 and 3 that are spaced from the sides of the loop 1 and diverge upwardly with relation thereto. The material is bent inwardly and 65 laterally at the upper extremities of the arms 2 and 3 to provide locking shoulders 4 and 5. From the shoulders 4 and 5 the material is bent rearwardly and upwardly in an inclined plane to provide inclined offset 70 portions 6 and 7 which are adapted to engage the ends of a button hole as clearly shown in Fig. 2 in the drawings. From the upper ends of the portions 6 and 7 the material is bent to form outwardly extending 75 arms 8 and 9 that are disposed at right angles to the portions 6 and 7 and in the same plane as compared with the shoulders 4 and 5.

The arms 8 and 9 are adapted to engage 80 one side of the neck band adjacent to the ends of the button hole and the shoulders 4 and 5 to engage the other side of the neck band at the ends of the button hole as will be clearly seen with reference to Fig. 2 in 85 the drawings. The structure described comprises the improved buttoning member forming a part of my device. It will be readily seen that the shoulders 4 and 5 are adapted to be moved inwardly toward one 90 another to facilitate the insertion of the button through the button holes and will automatically spring into extended position and lock as clearly shown in Fig. 2 in the drawings.

My improved tie slide is designated 10 as an entirety and is offset with relation to the buttoning member, said offset arrangement being provided by the offset portions 6 and 7 previously described.

My improved tie slide comprises upwardly extending arms 11 and 12 that are formed by bending the material upwardly at right angles to the arms 8 and 9. The arms 11 and 12 are comparatively longer 105 than the other straight portions of the device as a whole and are adapted to be grasped and forced toward one another to move the shoulders 4 and 5 inwardly so that the buttoning member may be inserted 110 into a button hole and by releasing the arms 11 and 12 the shoulders 4 and 5 will auto-

matically move into locking position. The material is bent downwardly and inwardly to provide guide arms 13 and 14 which converge at their inner ends and are spaced or offset with relation to the arms 11 and 12 to provide a space between the arms 13 and 14 and 11 and 12 of sufficient size to slidably receive a neck tie as shown in Fig. 1. The arm 13 is shorter than the one 14 and provided with an eye 15 formed at its free end and disposed in such a plane as to lie flat against the neck tie and collar. Adjacent its inner end the arm 14 is bent to provide a U-shaped loop 16 that is disposed with its open end uppermost and has an eye 17 formed on its free extremity. It will be noted with particular reference to Fig. 2 in the drawing that the lower end of the loop 16 is disposed below the arms 8 and 9 between the offset portions 6 and 7.

In operation to place a tie within the slide 10 the small part of the tie is inserted first between the arms 11 and 14 and then placed within the loop 16 and brought under the lower end of the arm 13 so as to be positioned between the arms 12 and 13. It will thus be seen that the loop 16 serves to prevent downward slipping of the tie. The upward slipping of the tie is prevented by the formation of the arms 11 and 14 and 12 and 13 with each other. When the tie is placed within the slide as described, the collar is opened sufficiently to enable the insertion of the buttoning member through the button hole of the collar at the rear thereof. The buttoning member is placed partly within the neck band button hole and by forcing down the collar the shoulders 4 and 5 will compress slightly and when forced within the button hole will automatically move into locking position as shown in Fig. 2 in the drawings.

It will be readily seen that the offsetting of the buttoning member with relation to the slide provides for the easy and ready securing of the collar. The device as a whole is formed comparatively flat so as not to bulge the collar or prove uncomfortable to the wearer. To unlock the buttoning member it is only necessary for the operator to move the arms 11 and 12 to-

ward each other thus effecting a similar movement of the shoulders 4 and 5 and enabling the buttoning member to be withdrawn from the button hole in the neck 55 band.

With reference to the foregoing description and accompanying drawings, it will be readily seen that I have provided an extremely simple and inexpensive combined 60 collar button and tie slide that may be formed of a single piece of preferably spring wire and operated in an easy, reliable and expeditious manner to attain the objects hereinbefore set forth.

In practice, I have found that the form of my invention, illustrated in the drawings and referred to in the above description, as the preferred embodiment, is the most efficient and practical; yet realizing that the 70 conditions concurrent with the adoption of my device will necessarily vary, I desire to emphasize the fact that various minor changes in details of construction, proportion and arrangement of parts may be re- 75 sorted to, when required, without sacrificing any of the advantages of my invention, as set forth.

What is claimed is:—

A combined collar button and tie slide 80 consisting of a single piece of metal, bent centrally to form an inverted U-shaped spring member having upwardly extending arms, shoulders formed by said arms bent inwardly and upwardly, said shoulders 85 adapted to engage the side wall of a button hole, the said upwardly extending portions having an outwardly directed portion, said metal piece being further bent upwardly from the outer ends of said last named arms, 90 and bent downwardly to provide guide arms, said last named arms being spaced from each other, certain of said last named arms being bent inwardly inclined and an open end loop formed on the lower end of 95 one of said inclined arms.

In testimony whereof I affix my signature in presence of two witnesses.

WILLIAM W. BROWN
